[57] CLAIM

The ornamental design for a trammel head, substantially
as shown and described.

DESCRIPTION

FIG. 1 is a top perspective view of a trammel head
showing my new design;

FIG. 2 is a right side elevational view thereof;

FIG. 3 is a bottom plan view thereof;

FIG. 4 is a front end elevational view thereof; and

FIG. 5 is a rear end elevational view thereof.

The environmental structure shown in dotted lines in
FIG. 1 is for illustrative purposes only and not a part of
the design claimed.
